CLAIM

We claim the ornamental design for a chest implant, as shown and described.

DESCRIPTION

FIG. 1 is a perspective view of a chest implant;
FIG. 2 is a top view thereof;
FIG. 3 is a top right view thereof;
FIG. 4 is a top right cross sectional view thereof taken along lines **28-28** of FIG. 2;
FIG. 5 is a right cross sectional view thereof taken along lines **28-28** of FIG. 2;
FIG. 6 is a bottom right cross sectional view thereof taken along lines **28-28** of FIG. 2;
FIG. 7 is a right view thereof;
FIG. 8 is a bottom right view thereof;
FIG. 9 is a bottom view thereof;
FIG. 10 is a bottom left view thereof;
FIG. 11 is a left view thereof;
FIG. 12 is a top left view thereof;
FIG. 13 is a top front view thereof;
FIG. 14 is a front view thereof;
FIG. 15 is a front bottom view thereof;
FIG. 16 is a back bottom view thereof;
FIG. 17 is a back view thereof;
FIG. 18 is a top back view thereof;
FIG. 19 is a top right front view thereof;
FIG. 20 is a top right back view thereof;
FIG. 21 is a top left back view thereof;
FIG. 22 is a top left front view thereof;
FIG. 23 is a bottom right front view thereof;
FIG. 24 is a bottom right back view thereof;
FIG. 25 is a bottom left back view thereof; and,
FIG. 26 is a bottom left front view thereof.
